UNITED STATES PATENT OFFICE

127,600

DESIGN FOR A PAIR OF SPECTACLES

Norman William Chappell, Amersham, England

Application August 2, 1940, Serial No. 94,152

Term of patent 14 years

To all whom it may concern:

Be it known that I, Norman William Chappell, a subject of the King of Great Britain, residing at Hithermead, Westanley Avenue, Amersham, Buckinghamshire, England, have invented a new, original, and ornamental Design for a Pair of Spectacles, of which the following is a specification, reference being had to the accompanying drawing, forming part thereof.

Figure 1 is a perspective view looking towards the front of a pair of spectacles, showing my new design.

Figure 2 is a top plan thereof, part of one of the temples being broken away for convenience of illustration.

Figure 3 is a side view, and

Figure 4 is a section on line 4—4 of Figure 1.

The dominating features of my design are shown in full lines on the drawing.

I claim:

The ornamental design for a pair of spectacles, as shown and described.

NORMAN WILLIAM CHAPPELL.
